(57) **CLAIM**

The ornamental design for a roofing deck ceiling system, as shown and described.

DESCRIPTION

FIG. 1 is an upper right front perspective view of a roofing deck ceiling system showing my new design in accordance with a first embodiment of the present invention;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is an upper right front perspective view of a roofing deck ceiling system showing my new design in accordance with a second embodiment of the present invention;

FIG. 9 is a top view thereof;

FIG. 10 is a bottom view thereof;

FIG. 11 is a left side view thereof;

FIG. 12 is a right side view thereof;

FIG. 13 is a front view thereof;

FIG. 14 is a rear view thereof;

FIG. 15 is an upper right front perspective view of a roofing deck ceiling system showing my new design in accordance with a third embodiment of the present invention;

FIG. 16 is a top view thereof;

FIG. 17 is a bottom view thereof;

FIG. 18 is a left side view thereof;

FIG. 19 is a right side view thereof;

FIG. 20 is front view thereof; and,

FIG. 21 is a rear view thereof.

The broken lines illustrate unclaimed portions and form no part of the claimed design. The broken away symbols in the drawings indicate indeterminate length and any portion of the article between the breakaway symbols form no part of the claimed design.

1 Claim, 15 Drawing Sheets
